METHOD AND DEVICE FOR HAIR DRESSING

Alfred L. Prosser, Brooklyn, N. Y.

Application July 30, 1932, Serial No. 626,299

7 Claims. (Cl. 132—43)

This invention relates to improvements in hair dressing devices, and more particularly to improved flexible members adapted to be used in retaining hair in curled or waved form, and the invention so includes an improved mandrel adapted for use with the novel hair dressing devices.

In the hair dressing art numerous devices have been proposed for use as aids in making and/or maintaining strands of hair in desired curl and/or wave forms. Most of these devices include stiff, non-bendable members which, while serving to maintain the hair in a desired shape, are uncomfortable to the wearer due to the fact that the stiff non-bendable members press into the scalp and cause discomfort to the wearer, if not actual abrasion and rupture of the skin.

This invention provides an improved hair dressing device and an auxiliary member which is adapted to serve as the retaining or locking means for the said device, as well as being adapted to serve as a mandrel about which the hair may be wound in locking engagement with the permanent member, the said hair dressing device being released from its engagement with the mandrel and permanently clamped about the curl or wave, the mandrel being thereafter removed.

The invention also relates to an improved mandrel adapted for use in hair dressing and more particularly adapted to serve as a support for hair gripping members while a curl or wave is being formed.

The invention also consists in forming a product having the general characteristics and applications and the several original features of utility hereinafter set forth and claimed, and to the process of using the same having certain new and original arrangements and combinations of steps, as will be better understood from the following description.

Although the novel features which are believed to be characteristic of this invention will be particularly pointed out in the claims appended hereto, the invention itself, as to its objects and advantages, the mode of its operation and the manner of its organization may be better understood by referring to the following description in which a particular commercial embodiment thereof is disclosed. It will be understood, however, that the features thereof may be modified in various respects without departing from the broad spirit and scope of the invention.

In the following description and in the claims the various steps and details comprising the invention will be identified by specific names, for convenience, but they are intended to be as generic in their application as the art will permit.

Fig. 1 is a front elevation of an improved mandrel adapted for use in hair dressing.

Fig. 2 is a view similar to Fig. 1, showing a modified form of the mandrel.

Fig. 3 is an elevation of a circular mandrel of the general type shown in Figs. 1 and 2.

Fig. 4 is a side view, partly in section, of the mandrel shown in Fig. 1, showing the method of securing a hair gripping member and introducing the strands of hair to grip same.

Fig. 5 is a view similar to Fig. 4 showing the method of forming a curl or wave, the ends of the gripping device being bent in locking position on the mandrel;

Fig. 6 is a view similar to Fig. 5, showing a completed curl and the ends of the hair gripping device removed from locking engagement with the mandrel;

Fig. 7 is an elevation showing the ends of the hair gripping device locking in position on the curl and the mandrel partially withdrawn from the curl;

Fig. 8 is an elevation of a completed curl with the gripping or locking member in position;

Fig. 9 is a phantom view of a modified form of hair gripping device removably mounted on a mandrel with hair wound therearound; and

Fig. 10 is an elevation of the curl formed in Fig. 9 with the hair gripping device in completed locking condition.

Referring more particularly to the drawing, the improved mandrel of the present invention comprises an elongated member 10 of any suitable material such as wood and generally rectangular in shape. This member may be provided with a pointed end 11 and a slotted end 12, whose function will appear more in detail hereinafter. The mandrel may have retaining slots at both ends, as indicated more particularly in Fig. 2, the extra slot being indicated by the numeral 12a. In addition, the gripping slot or slots may be joined on the sides of the mandrel, as indicated generally by the numeral 12b, and such laterally disposed gripping slots may be positioned at any desired place along the length of the mandrel. As indicated at 12c, the gripping slots may be disposed interiorly of the body of the mandrel, and may also be suitably positioned along its length. As shown in Fig. 3, the mandrel 10a, instead of being rectangular, may have any desired configuration and is shown circular, although it will, of course, be appreciated that the device may be polygonal, square, ellipsoidal or any other desired shape. The mandrels are preferably provided with a plurality of transverse apertures 13, of any desired size and number, which are adapted to retain a hair dressing clamping member or device 20, of any desired length.

As shown in Fig. 4, the member 20 is intended for wide curls or waves and is passed through the lowermost hole 13a at one end and is gripped in the slot 12 at the other end. Where smaller

curls or waves are to be formed, the members 20 will be correspondingly reduced in length and the appropriate intermediate apertures 13 will be made use of.

5 In hair dressing parlors where a number of operators are engaged and a great number of standard curls and waves are being formed, the members 10 may be of a desired overall length and slotted at one or both ends. Also in such 10 instances, a sufficient number of mandrels 10b of different sizes will be provided for use with the various types of curls and/or waves. However, the mandrel may be provided with the transverse apertures 13 if desired.

15 In hair dressing, to form curls or waves, the hair is preferably washed and then treated with a suitable hair dressing lotion, after which the strands 30 are passed between the member 20 and the body of the mandrel 10, whereupon the 20 ends 21 and 22 of the hair gripping member are bent flat against the face of the mandrel so as to be locked thereagainst. In this position the curl or wave 31 is formed by winding the hair 30 around the mandrel and the associated gripping 25 member 20 as tightly as may be desired. The width of the curl or wave is determined by the length of the mandrel and the position of the ends 21, 22 of the hair dressing device.

30 After a sufficient amount of hair has been wound on the mandrel, the ends 21 and 22 are severally withdrawn from the retaining slot 12 and the aperture 13a and bent rearwardly as indicated in Fig. 6. These ends 21 and 22 of member 20 are then brought together and forced downwardly into the body of the curl or wave 31 so as to retain the latter locked between themselves and the body of the hair dressing device 20. The mandrel 10 is then withdrawn, as indicated, in Fig. 7. The finished curl or wave, as shown in 40 Fig. 8, will thus comprise a mass of hair 31 arranged in curl or wave form about the body portion 20 of the clamping member, the curl being held and locked in position by the co-action of the ends 21, 22 with the body portion 45 of the gripping member.

Referring more particularly to Figs. 9 and 10, a modified method of arranging or forming curls or waves is shown in which a gripping member 20a is held at its central point by the gripping 50 slot 12 of the mandrel 10. The hair 30 may thereafter be wound about the mandrel and the parallel legs 23, 24 of the member 20a, the ends of the strands being held in engagement between the legs and the body of the mandrel. 55 After winding the hair about the novel mandrel assembly to form a desired curl 31a, the mandrel is withdrawn from the member 20a and the curl 31a and the free ends 25, 26 of the parallel members 23, 24 are brought into locking engagement with the closed end or loop 27 at the other end of the device so as to lock the hair or curl in position. This particular device is specially suited for the making of the small curls where the support is to be permanently associated with 60 the curl.

It will now be appreciated that there has been provided a variety of improvements in hair treating methods, and more particularly novel members for use in curling and waving, which members include novel mandrels adapted to take a variety of sizes of gripping members for curls or waves and which mandrels permit the formation

of any desired shape and style of curl or wave, at the same time permitting the insertion in said curls or waves of locking members adapted to be permanently associated therewith.

The invention also comprehends the utilization 80 of such hair gripping members in a variety of forms and permits the formation of curls and/or waves rapidly and economically as well as imparting a maximum of comfort to the wearer.

Although certain novel features of the invention have been shown and described and are pointed out in the annexed claims, it will be understood that various omissions, substitutions and changes in the form and details of the devices illustrated and the process of their use may be 90 made by those skilled in the art without departing from the spirit of the invention.

What is claimed is:

1. An improved rigid, removable mandrel for hair dressing, comprising an elongated body 95 member having a plurality of apertures therein, said apertures being adapted to receive a bendable, flexible hair-gripping member.

2. An improved rigid, removable mandrel for hair dressing, comprising an elongated body 100 member having a plurality of apertures therein, at least one of said apertures being disposed at an end of the mandrel and forming a gripping slot, said apertures being adapted to receive a bendable, flexible hair-gripping member.

3. An improved rigid, removable mandrel for hair dressing comprising an elongated body member having a plurality of apertures therein, at least one of said apertures being disposed at an end of the mandrel and forming a gripping slot, 110 and others of said apertures being formed in the body of the mandrel and transversely of the longitudinal axis thereof, said apertures being adapted to receive a bendable, flexible hair-gripping member.

4. A combination hair dressing device comprising a rigid, removable mandrel having apertures 115 therein and at least one gripping slot, and a universally bendable flexible hair gripping member threaded through one of said apertures and removably held in said slot.

5. A combination hair dressing device, comprising an apertured rigid mandrel and a universally bendable, flexible hair gripping member removably held by the apertures of the mandrel.

6. The improved method of forming hair into waves and curls comprising winding a strand of hair about a core comprising a rigid mandrel and a universally bendable, flexible hair gripping member removably locked thereon, removing the 130 ends of the gripping member from their association with the mandrel and disposing the said ends in clamping locking engagement about the wound hair.

7. The improved method of forming hair into 135 waves and curls comprising clamping the ends of a strand of hair between a rigid mandrel and a universally bendable, flexible hair gripping member removably secured on and by said mandrel; winding the strand of hair about the mandrel and associated gripping member as a core; removing the ends of the gripping member from engagement with the mandrel and disposing them in clamping locking engagement about the wound hair; and thereafter withdrawing the mandrel.

ALFRED L. PROSSER.
